US0D1033894S

(12) **United States Design Patent** (10) **Patent No.:** **US D1,033,894 S**
(45) **Date of Patent:** **** Jul. 9, 2024**

(54) **CASE FOR PORTABLE ELECTRONIC DEVICE**

(71) Applicant: **SAMSUNG ELECTRONICS CO., LTD.**, Suwon-si (KR)

(72) Inventors: **Sungjin Yum**, Suwon-si (KR); **Minah Koh**, Suwon-si (KR); **Hakdo Kim**, Suwon-si (KR)

(73) Assignee: **SAMSUNG ELECTRONICS CO., LTD.**, Gyeonggi-Do (KR)

(**) Term: **15 Years**

(21) Appl. No.: **29/745,643**

(22) Filed: **Aug. 7, 2020**

(30) **Foreign Application Priority Data**

Feb. 13, 2020 (KR) 30-2020-0006367

(51) **LOC (14) Cl.** **03-01**

(57) **CLAIM**

The ornamental design for a case for portable electronic device, as shown and described.

DESCRIPTION

FIG. 1 is a front perspective view of a case for portable electronic device, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the portion 9 in FIG. 1;

FIG. 10 is an enlarged view of the portion 10 in FIG. 2; and,

FIG. 11 is an enlarged view of the portion 11 in FIG. 4.

The even-dash broken lines in the figures depict portions of the case for portable electronic device which form no part of the claimed design. The dot-dot-dash broken lines encircling enlargement portions of the claimed design form no part of the claimed design.

1 Claim, 9 Drawing Sheets
